CLAIM

The ornamental design for a hair dryer, as described.

DESCRIPTION

FIG. 1 is a top right perspective view of a hair dryer
showing my new design;

FIG. 2 is a top left perspective view thereof;

FIG. 3 is a rear elevational view thereof;

FIG. 4 is a front elevational view thereof; and,

FIG. 5 is a right side elevational view thereof.

The bottom of the hair dryer is plain except for the
electrical lead extending therefrom.

The undisclosed bottom portion of the handle element
is flat and plain except for the appearance of the cord.

Fig. 1.
